United States Patent Office

Des. 178,931
Patented Oct. 9, 1956

178,931

FOOD TRAY

Clarence R. Perkins, Kinsman, Ohio

Application March 22, 1956, Serial No. 40,735

Term of patent 14 years

(Cl. D58—26)

Fig. 1

I claim:

The ornamental design for a food tray, substantially as shown.
